ABSTRACT OF THE DISCLOSURE

A method of and apparatus for treating fibrous materials provides an upright treating chamber filled with fibrous material. Additional fibrous material is continuously added at one end of the treating chamber, and a corresponding quantity of fibrous material is continuously withdrawn at the other end of the treating chamber so that new fibrous material added advances through the treating chamber from one to the other end thereof. An aerosol is introduced into the treating chamber for passage through the fibrous material therewithin either in concurrent flow with the fibrous material, or in counter-flow thereto. At the respectively opposite end of the treating chamber the aerosol is withdrawn.

BACKGROUND OF THE INVENTION

The present invention relates to the treatment of fibrous materials, and more particularly to the treatment of fibrous materials with aerosols. Still more specifically, the present invention relates to a method of treating fibrous materials with aerosols and to an apparatus for carrying out the method.

It is already known to treat fibrous materials, for instance textile materials, with aerosols for various purposes. The reasons for such treatments are well known and need not be discussed. It suffices to state that it is known to apply liquid aerosols to the surface of a fibrous layer. However, it is necessary to attain a uniform treatment of the fibrous material. This, it has been found, can be obtained only by applying the aerosol in excessive quantities to the fibrous layer and subsequently to remove this excess on a padding or foulard machine. Fibrous layers treated in this manner were of necessity relatively thin so that this approach to the treating of fibrous materials with aerosols has been less than satisfactory.

In another approach to treating fibrous materials with aerosols it is known to advance the fibrous material pneumatically through the pipeline in contact with aerosol. While this has resulted in uniform separation of the aerosol onto the fibers of the fibrous material that is a uniform treatment of the fibrous material, it has not been found feasible from an economic point of view because a predominant portion of the aerosol particles failed to adhere to the pneumatically advanced fibrous material and thus did not accomplish its intended purpose.

An additional approach which has been tried consists in the circulation of a solid dyestuff aerosol through a fluid bed of fibrous material which is to be dyed by resort to the aerosol process. Again, however, it has been found that this did not lead to a uniform and economic utilization of the aerosol. The fibrous material in a fluidizing process cannot be thoroughly and permanently enough opened, and is always subject to the formation of fiber agglomerations or "flocks" which make a uniform separation of the aerosol particles and their adherence on the fibers impossible. Furthermore, a single passage of the aerosol through the layer of fluidized fibrous material

2

is capable of effecting only partial treatment of the fibrous material because of the aforementioned poor separation of aerosol particles, so that this approach required several successive treatment stages in which the aerosol had to be passed through the fluidized fibrous material in each case. Finally, another approach has been used, namely the filtration of aerosols through a stationary layer of fibrous material. However, in such process it is well known that the amount of aerosol particles separated and adhered to the fibers depends on the concentration of such particles in the respective aerosol being used for the treatment. Thus, when filtering a mono-dispersion aerosol through a layer of stationary fibrous material, the concentration particles in the aerosol shows a decreasing tendency, that is the concentration of particles decreases as the pistons from the entry surface increases, and this decrease involves an approximately non-linear relationship. An analogous phenomenon is observed with respect to the concentration of aerosol particles deposited on the fibers. This decrease in concentration is even more remarkable if polydispersion aerosols are used. Thus it has been found that a uniform distribution and adherence of aerosol particles within the entire stationary layer of fibrous material is practically impossible.

The purpose of the present invention and the basic object of the same is to overcome the aforementioned disadvantages and to significantly improve the treatment of fibrous materials with aerosols.

SUMMARY OF THE INVENTION

In accordance with one feature of our invention we provide a method of treating fibrous materials with aerosols, which comprises the confining of a mass of fibrous material in an enclosed space having two opposite sides, the continuous addition of new fibrous material to this mass at one side of the space and the continuous withdrawal of fibrous material from the mass at the opposite other side, so that the new material which is being added to the mass at the aforementioned one side will advance in this space to the other side thereof. As this advancing of the fibrous material through the space takes place, we continuously provide for the passage of an aerosol through the mass of fibrous material in a predetermined direction to thereby effect substantially uniform distribution of the aerosol throughout the fibrous material in the space.

Inasmuch as we advantageously add and withdraw fibrous material at identical rates, the fibrous material within the enclosed space will undergo uniform movement so that the mass of moving fibers constitutes in effect a filtering medium. The aerosol is either sucked or forced, or both, through this filtering medium. In actual practice we prefer a simultaneous coaction of superatmospheric and subatmospheric pressures, particularly if the treatment effects relatively thick layers or masses of fibrous materials. Of course, it will be obvious that various different types of fibrous materials can be treated in this manner, that is have the aerosol particles adhere thereto during passage of the aerosol through the fibrous material. We are primarily concerned here with textile fibers, that is fibers suitable for the manufacture of textiles. Different natural and artificial fibers and blends thereof are suitable for this purpose. It should be understood, however, that the method and apparatus according to the present invention are applicable to aerosol treatment of fibers regardless of the intended use of such fibers.

It will be clear that, inasmuch as the continuously newly added fibrous material in effect continuously forms an entire new filtering layer at the one side of the enclosed space and inasmuch as the fibers are moved through the enclosed space at a predetermined rate so that the newly formed filtering layer advances successively in the direction away from the filter surface, that is the sur-

face at which the aerosol is directed for instruction into the layer of fibrous material, it is in effect this filter layer within which—that is to whose fibers—the major concentration of the incoming aerosol particles adheres. As each filter layer moves away from the filter surface, it receives fewer and fewer aerosol particles whereas the new filter layer, that is the filter layer which builds up upstream of the one just discussed because of the addition of new fibrous materials, now similarly undergoes treatment with the aerosol particles. When considering constant density or porosity value of the fibrous filtering medium, as well as a constant rate of the filtering process, the separability of the aerosol particles—that is the distribution and adherence of such particles within the filter layer—is proportional to the thickness of each filter layer. On the other hand, with a constant filter thickness the separability of the aerosol particles can be increased by rendering the filtering medium denser. Thus, the desired separation of the aerosol particles on the fibers of the respective filter layer can be obtained by selecting a suitable thickness or density of the filtering medium, respectively. Evidently, these two parameters should be chosen so as to provide for optimum economy in consumption of the aerosol during a single passage of aerosol particles through the fibrous material.

We have further found that it is possible to influence the separation of the aerosol particles by changing the filtration speed. With the exception of extremely low speeds, the separation of aerosol particles is proportional to the filtration speed and the rate of separation increase depends mostly on the size of the aerosol particles as well as on the diameter of the fibers which form the filter layer.

Finally, it should also be noted that the amount of aerosol particles which adhere uniformly to each of the advancing fibrous layers or filter layers that is to the fibers which make up each such layer, can be controlled by varying the concentration of aerosol. Obviously, if low aerosol concentrations are used, the amount of particles adhered to the fibers within a given filter layer will be smaller than with highly concentrated aerosols, and vice versa.

In accordance with our invention the aerosol is caused to penetrate the mass of fibrous material either in concurrent flow, that is in the direction of movement of the mass of fibrous material or in counterflow, that is opposite the direction of movement of the fibrous material. Thus, the amounts of aerosol particles separated within each of the advancing layers of fibrous material are alike.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWING

FIG. 1 is a somewhat schematic vertical sectional view of an apparatus for the treatment of fibrous materials with aerosols by a method employing concurrent aerosol flow; and

FIG. 2 is a view similar to FIG. 1, but illustrating the apparatus employing countercurrent flow of the aerosol.

DESCRIPTION OF THE PREFERRED EMBODIMENTS

Discussing now the drawing in detail, and firstly FIG. 1 thereof, it will be seen that reference numeral 1 identifies a substantially vertical chamber which is advantageously of hollow cylindrical configuration. In the upper section 2 of this chamber, there is arranged a fiber feed mechanism 3 whereas in the lower section 4, which is of somewhat

flared cross-section there is provided a fiber removal mechanism 5.

The feed mechanism 3 for the addition of fibrous material comprises a knurled feed roller 6 with a feed table 7 attached thereto. A fiber-opening roller 8 is provided with a saw-tooth type cover 9 whose teeth when they engage the fibrous material, effect opening or separation of the fibers. The feed roller 6 is rotated via a transmission element 10 by a suitable electric motor 11; the fiber-opening roller 8 is similarly operated by an electric motor 13 via the transmission element 12. The direction of rotation of feed roller 6 is indicated by the arrow S1 and that of the fiber-opening roller 8 is indicated by the arrow S2.

The fiber-removing or withdrawing mechanism 5 provided in the section 4 of the chamber 1 comprises a knurled roller 14 which cooperates with a suction-type screen cage 15 attached thereto. The cage 15 will be described in more detail but at this point it is sufficient to state that the cage 15 is coupled with the roller 14 via a transmission element 16, and via an additional transmission element 17 with an electric motor 18. Thus, the roller 14 and the cage 15 are rotated as indicated by the arrows S3 and S4, respectively.

The section 4 of the chamber 1 narrows to an outlet opening 19 below the fiber withdrawing mechanism 5, and this outlet 19 communicates with a hopper-type feeder 20 of a pneumatic delivery tube 21 which latter communicates with a fan 22 whose operation effects in the tube 21 a stream of moving air, that is a condition of superatmospheric pressure which suffices for conveying fibers entering into the tube 21, through the hopper 20 and for advancing these fibers in the tube 21 in the direction of the arrow S5. Fan 22 is driven via a transmission element 33 by an electric motor 24, as clearly shown.

Returning now to the suction-type screen cage, it is pointed out that this is provided with internal stationary baffle 25, as also clearly shown in the drawing. The screen cage is of course of known construction and is located oppositely and in parallelism with the roller 14. The interior of the screen cage 15 communicates via a conduit 26 with the fan 27, the latter being driven by means of a transmission element 28 from an electric motor 29. The purpose of the screen cage 15 is to aspirate or withdraw aerosol from the interior of the chamber 1.

An aerosol inlet means 30 is provided in the region of the upper section 2 of the chamber 1 and in this instance consists of a tubular ring having jets 31 through which aerosol can issue. The ring communicates via a conduit 32 with the fan 27. Arranged within the conduit 32 upstream of the ring, that is upstream of the jets 31, there is arranged an electric heating element 33 which is connected to a non-illustrated source of electric energy. A regulating flap or damper 34 is pivotally arranged within the conduit 32 upstream of the heating element 33 and serves for directing the flow of air over the heating element. An aerosol generator 35 of known construction is connected with the conduit 32 via the branch pipes 36 and 37 which respectively communicate with the conduit 32 upstream of the damper 34 and downstream of the heating element 33. The generator 35 is equipped with a known aerosol-concentration controlling device 38. Neither the construction of the generator 35 nor that of the device 38 is of importance for the purposes of the present invention.

The arrow S6 and the arrow S7 indicate the direction of flow of an air current produced by the fan 27 and moving through the conduit 32; the direction of the air current entering the aerosol generator 35 from the conduit 32, and reentering the conduit 32 from the aerosol generator 35, is indicated by the arrows S8 and S9, respectively.

If desired, a known device 39, connected to a source 40 of high voltage, may be arranged in the conduit 32 upstream of the aerosol inlet means 30 for the purpose of charging the aerosol particles by means of corona discharge.

The chamber 1 is provided with an external jacket or sleeve 41 to which hot steam or other heat-exchanging fluid is supplied via conduit 42 and withdrawn via a conduit 43. Inasmuch as steam is assumed to be the heat-exchanging fluid in the illustrated embodiment of FIG. 1, a valve 44 is provided for withdrawal of the condensate.

It will be seen that the construction of the chamber 1 and the arrangement of the feed mechanism 3 and the withdrawal mechanism 5 therewithin is such that the chamber 1 constitutes an integral housing which is closed with reference to ambient atmosphere.

In accordance with the invention the output rate of the feed mechanism 3, and the withdrawal rate of the withdrawal mechanism 5 are alike, so that the quantity of new fibrous material supplied into the upper section 2 of the housing 1, that is onto the uppermost surface of the mass of fibrous material already contained in the housing 1, is identical with the amount of fibers withdrawn from this mass at the lower section 4 by the withdrawal mechanism 5.

The apparatus illustrated in FIG. 1 is particularly suitable for the dyeing of polyester staple fibers with a dispersion dyestuff aerosol. The polyester staple fibers 57 are continuously supplied from a preparatory spinning plant to the feed table 7. They are opened to flocks in the feed mechanism 3, and these flocks are then hurled into the interior of the cylindrical chamber 1 where they are deposited onto the homogeneous fibrous mass contained therewithin. Once the chamber 1 has been filled to the level of the aerosol inlet means 30, the withdrawal mechanism 5, and the fan 27 and aerosol generator 35 are started simultaneously. Withdrawal of fibrous material by the withdrawing mechanism 5 results in downward movement of the mass 58 of fibrous material in the chamber 1. Thus, the uppermost surface or layer of the mass 58 is continuously renewed by the addition of fresh untreated fibers thereto via the feed mechanism 3. This downward movement of the mass 58 is identified with the arrow S16.

The aerosol in form of a dispersion dyestuff is introduced into the chamber 1 via the aerosol inlet means 30. As a result to the suction effect produced by presence of sub-atmospheric pressure in the screen cage 15 the aerosol penetrates the mass 58 of fibrous material in the direction of the arrow S17, that is in concurrent flow with the direction of movement of the fibrous material 58. During this passage through the fibrous material, the aerosol particles adhere to the polyester staple fibers 57 which make up the mass or body 58. Once the aerosol has passed through the mass 58, and has thus been substantially consumed in the treating process, the remainder is sucked off in the direction of the arrows S18 into the screen cage 15 and to the fan 27 from where it is returned through the conduit 32 over the electric heating element 33 back to the inlet means 30 where it is combined or mixed with fresh aerosol. A portion of the substantially consumed aerosol aspirated into the screen cage 15, that is almost pure remaining air, is vented by means of the distributing flap 34 into the branch pipe 36 and from there to the aerosol generator 35. There it is saturated with fresh aerosol, mixed with heated air, and supplied to the aerosol inlet means 30 for admission through the jets or nozzles 31 thereof into the chamber 1. The electrical charge of the aerosol particles is effected by means of the device 39, if such a device is provided.

The chamber 1 is preheated to a suitable dyeing temperature, so that, after the aerosol particles in form of a dispersion dyestuff are uniformly adhered to the polyester staple fibers 57 they are dissolved on these fibers whereby the latter are colored. The concentration of the aerosol is adjusted by means of the device 38.

With this construction a perfect coloration of the polyester fibers is obtained during a single passage of the aerosol and of the fibers through the chamber 1 without necessitating the use of finishing processes, such as fixa-

tion, soaping, or washing or the like which are required in the previously known dyeing methods.

The apparatus illustrated in FIG. 2 is substantially similar to that of FIG. 1. It also comprises a feed mechanism 3 corresponding to that shown in FIG. 1. The withdrawal mechanism 5a utilized in FIG. 2 comprises a pair of knurled rollers 45 and 46 which are coupled for joint rotation by means of a transmission element 47 so that they can be driven simultaneously by an electric motor 48. The arrows S10 and S11 indicate the direction of rotation of the rollers 45 and 46. It will be appreciated that suitable arrangement must be provided for effecting this oppositely directed rotation of the two rollers, but such arrangements are well known to those skilled in the art. The rollers 45 and 46 are arranged below a relatively narrow outlet opening 49 in the section 4 of the chamber 1a, and downwardly of this outlet opening 49 and of the rollers 45, 46 there is arranged a hopper feeder 50 which supplies fibers withdrawn by the rollers 45 and 46 and deposited in the hopper feeder 50 onto a conveyor belt 51 which is driven in the direction indicated by the arrow S12 via a transmission element 52 and an electric motor 53.

Contrary to the embodiment of FIG. 1, the aerosol inlet means 30a in FIG. 2 is arranged in the section 4 of the chamber 1, that is in the lowermost part of the latter. The tubular ring provided with the outlet jets or nozzles 31a is connected to a main conduit 54 which communicates with the aerosol generator 35 and the fan 27, both of which are identical with constructions shown in FIG. 1. The fan 27 in turn is connected to a suction device consisting of a tubular ring 55 with nozzles 56, this ring being arranged in the uppermost section 2 of the chamber 1a.

The arrow S13 indicates the direction in which an air current moves from the ring 55 to the fan 27, and the direction of the air current from the fan 27 to the aerosol inlet means 30a is identified by arrow S14. Arrows S8 and S7 respectively indicate the direction of an air current passing from the conduit 54 into the aerosol generator 35, and from the latter back into the conduit 54 downstream of the air current regulating flap 34 installed in the conduit 54. To prevent the individual fibers from being entrained into the nozzles 31a and 56 of the aerosol inlet means 30a and the tubular ring 55, respectively, the nozzles 31a and 56 are covered with a fine tulle knitting (not illustrated). As in the embodiment of FIG. 1, the chamber 1a with the feed mechanism 3 constitutes an integral closed housing. No heating element corresponding to the element 33 of FIG. 1 is provided.

The apparatus of FIG. 2 is particularly well suited for lubricating wool fibers 59 with an aerosol lubricating agent. In this embodiment the aerosol is caused to penetrate the layer or mass 58a of wool fibers, which advances in the direction of the arrow S16, and this penetration results from the presence of a sub-atmospheric pressure produced by the suction device 55. As is clearly evident, the aerosol in this embodiment moves countercurrent to the direction of advancement of the mass 58a, as indicated by the arrows S20 for the movement of aerosol, and the arrows S16 for the movement of the fibrous mass 58a. During this relative movement the lubricating agent adheres to the wool fibers. The substantially consumed aerosol is aspirated out of the chamber 1, in the direction of the arrow S20, as already indicated and recirculated through the main conduit 54, to the aerosol inlet means 30a and therefrom back into the chamber 1. A portion of the recirculated aerosol is introduced by means of the flap 34 into the branch pipe 36 and from there into the aerosol generator 35. Therein it is saturated with new aerosol and is then returned via the branch pipe 37 to the conduit 54 and thence to the aerosol inlet means 30a. The aerosol concentration is again determined by the aerosol concentration controlling device 38.

The wool fibers lubricated in the embodiment of FIG. 2 are withdrawn at the outlet 49 by the rollers 45 and 46 and are supplied by these rollers into the hopper feeder

50 from where they drop onto the conveyor belt 51 which supplies them to another processing station. The treatment in this embodiment proceeds at room temperature and results in uniform and economic lubrication of the wool fibers.

It is to be noted that the dispersed phase of the aerosols which are to be used in accordance with the present invention may be solid, liquid or mixed. Aerosols having solid particles dispersed therein may be used, for instance, in processes for optically brightening or dyeing synthetic fibers. Liquid aerosols may be used for lubricating, condition, graphiting or other ways of treating natural or man-made fibers. Aerosol blends comprising solid particles of a dispersion dyestuff and liquid aqueous particles may be used for various different purposes, e.g. for the dyeing of synthetic fibers.

As already indicated the present invention will be carried out at room temperature (embodiment of FIG. 2) or at elevated temperatures (embodiment of FIG. 1). The room temperature processing is preferable in certain circumstances, for example, when liquid aerosols are to be used. Elevated temperatures, on the other hand, are particularly advantageous if solid-particle aerosols are employed or in cases where the aerosol particles are to be dissolved on the fibers or into the fibers after having been deposited thereon, or are intended to enter into a chemical reaction with the fibers.

As also clear from the preceding disclosure, the method according to the present invention may be performed at atmospheric pressure, at sub-atmospheric pressure or at super-atmospheric pressure. Sub-atmospheric and super-atmospheric pressure may be used, for example, for the purpose of accelerating the dissolution of the aerosol particles in fibers, or for accelerating or retarding a chemical reaction between the fibers and the aerosol particles adhered thereto.

Separability of the aerosol particles within the layer or mass of fibrous material is further enhanced if the aerosol particles and/or the fibrous material to be treated are provided with an electric charge which may be either unipolar, or bipolar. It is preferred that if the aerosol particles are so charged, they be provided with a unipolar charge because this contributes to an increase of the separability or distribution of these particles. Charging of the aerosol particles can be effected by means of corona discharge, by ultra-violet irradiation, from a radioactive source or the like. All of this is known and is mentioned here only for purposes of complete description. On the other hand, the fibrous material can be charged by moving it in an electrostatic field between electrodes of a capacitor connected to a high voltage source. Because of different dielectric constants of the aerosol vehicle and the fibrous material to be treated, the strength of the electrostatic field increases in the direction towards the fibers. The particles bearing the opposite charge, as well as the uncharged particles, are attracted to the fibers in the direction of increasing gradient of the electrostatic field. In separating actions caused by electrostatically charged mechanisms natural charges of the aerosol particles can be utilized. Again, this is mentioned here not as a basic concept of the invention, but only for the sake of completeness, such expedients already being known in the art.

It will be understood that each of the elements described above, or two or more together may also find a useful application in other types of constructions differing from the types described above.

While the invention has been illustrated and described as embodied in a method and apparatus for treating fibrous materials with aerosols, it is not intended to be limited to the details shown, since various modifications and structural changes may be made without departing in any way from the spirit of the present invention.

Without further analysis, the foregoing will so fully reveal the gist of the present invention that others can

by applying current knowledge readily adapt it for various applications without omitting features that from the standpoint of prior art clearly constitute essential characteristics of the generic or specific aspects of this invention and therefore, such adaptations should and are intended to be comprehended within the meaning and range of equivalence of the following claims.

What is claimed as new and desired to be protected by Letters Patent is set forth in the appended claims:

1. A method of treating fibrous materials with aerosols in an enclosed space having an upper and a lower portion, comprising the steps of introducing into said upper portion of said enclosed space tufts of fibrous material for gravity descent to said lower portion, to thereby provide in said enclosed space a layer of said fibrous material having an upper and a lower side and a thickness smaller than the height of said enclosed space; continuously introducing first quantities of additional tufts of said fibrous material into said upper portion of said enclosed space for gravity descent onto said upper side of said layer, and continuously withdrawing from said lower side of said layer second quantities of fibrous material substantially identical to said first quantities, so that said layer is continuously renewed as a result of gravity descent of said first quantities from said upper side to said lower side of said layer; and continuously passing through the thus constantly renewed layer of fibrous material an aerosol in predetermined direction from one to the other of said sides so as to effect filtration of said aerosol through said layer to thereby treat the fibers of said layer with said aerosol.
2. A method as defined in claim 1; and further comprising the step of maintaining atmospheric pressure at said one side and sub-atmospheric pressure at said other side.
3. A method as defined in claim 1; and further comprising the step of maintaining super-atmospheric pressure at said one side and at most atmospheric pressure at said other side.
4. A method as defined in claim 1, wherein said aerosol is passed through said layer in predetermined direction from said upper to said lower side.
5. A method as defined in claim 1, wherein said aerosol is passed through said layer in predetermined direction from said lower to said upper side.
6. A method as defined in claim 1, the step of passing an aerosol through said mass comprising ejecting the aerosol from an aerosol generator; and further comprising the step of withdrawing the spent gaseous phase of the aerosol from said space at said other side, and recirculating at least some of the spent gaseous phase to said aerosol generator.
7. Apparatus for treating fibrous materials with aerosols, comprising, in combination, confining means defining an enclosed space having an upper and a lower portion, for confining a layer of fibrous material which tends to descend under the influence of gravity from said upper portion to said lower portion; feed means for continuously introducing into said upper portion first quantities of tufts of fibrous material for gravity descent onto an upper side of said layer; withdrawing means for continuously withdrawing from a lower side of said layer second quantities of fibrous material which are substantially identical to said first quantities, so that said layer is continuously renewed as a result of gravity descent of said first quantities from said upper side to said lower side of said layer; and treating means for continuously passing an aerosol through said layer from one to the other of said sides thereof, so as to effect filtration of said aerosol through said layer to thereby treat the fibers of said layer with said aerosol.
8. Apparatus as defined in claim 7, wherein said confining means comprises wall means defining a substantially vertical chamber.
9. Apparatus as defined in claim 8, wherein said chamber is of hollow cylindrical configuration.

10. Apparatus as defined in claim 8, wherein said treating means comprises supply means communicating with said upper portion for advancement of the aerosol in direction to said lower portion concurrently with the movement of said fibrous material.

11. Apparatus as defined in claim 10; and further comprising suction-producing means communicating with said enclosed space at said lower portion thereof for facilitating advancement of said aerosol through said layer of fibrous material, and for removing from said enclosed space such aerosol which penetrates through said layer of fibrous material to said lower portion.

12. Apparatus as defined in claim 8, wherein said treating means comprises supply means communicating with said lower portion for advancement of the aerosol in direction to said upper portion countercurrent to the movement of said fibrous material through said chamber.

13. Apparatus as defined in claim 12; and further comprising suction-producing means communicating with said enclosed space at said upper portion thereof for facilitating advancement of said aerosol through said layer of

10
5 fibrous material, and for removing from said enclosed space such aerosol which penetrates through said layer of fibrous material.

14. Apparatus as defined in claim 8, said treating means comprising aerosol supply means communicating with said upper portion for introducing said aerosol into said enclosed space and suction-producing means communicating with said enclosed space at said lower portion for removing residual aerosol from said enclosed space.

15. Apparatus as defined in claim 14; and further comprising returning means for returning the residual aerosol to said aerosol supply means.
